UNITED STATES PATENT OFFICE.

PETER L. DE VOIST, OF DULUTH, MINNESOTA.

OVERALLS.

1,191,288.

Specification of Letters Patent. Patented July 18, 1916.

Application filed September 23, 1915. Serial No. 52,263.

To all whom it may concern:

Be it known that I, PETER L. DE VOIST, a citizen of the United States of America, and resident of Duluth, in the county of St. Louis and State of Minnesota, have invented 5 certain new and useful Improvements in Overalls, of which the following is a specification.

This invention relates to apparel and particularly to overalls, the said invention being primarily designed as a protecting garment which may be utilized without regard to the back or front as the overalls are interchangeable with respect to such positions 15 and in this respect are distinctly advantageous as compared with overalls now in general use.

An object of this invention is to provide a garment of this type which will fit loosely 20 and will prove comfortable, the same having a reversible bib which is alike at the front and back and may be worn alternatively by changing from back to front according to the condition of the garment, or the pleasure 25 of the wearer.

It is a known fact that the wear on overalls comes usually on the front and with a garment of the type referred to herein, reversal of the position of the garment will 30 cause practically uniform wear on the two sides and will increase the durability of the said garment.

The ordinary bib overalls have a front opening, but in the present invention the 35 opening extends from side to side, the crotch portion being open and provided with such appropriate fastenings, thus preventing ripping at the point where it generally occurs; furthermore, the strain or binding which is 40 present in overalls of the ordinary type is obviated.

By reason of the fact that the invention is of the structure mentioned in a general way, advantages result and the garment may be 45 put on or taken off expeditiously.

With the foregoing and other objects in view, the invention consists in the details of construction, and in the arrangement and combination of parts to be hereinafter more 50 fully set forth and claimed.

In describing the invention in detail, reference will be had to the accompanying drawings forming part of this specification wherein like characters denote corresponding parts in the several views, and in 55 which—

Figure 1 illustrates a view in perspective showing one side of the garment; Fig. 2 illustrates a view in perspective showing the opposite side; and Fig. 3 illustrates a view 60 in perspective showing the garment removed from the wearer.

In these drawings 4 denotes one bib of the garment and 5 the other bib thereof, which bibs are practically of uniform construction. The leg portions 6 and 7 have 65 side openings at their tops as shown at 8, the said portions of the garment at the opening being secured together by fastenings such as 9, it being understood that these openings 70 are provided at each side.

The crotch portion 10 has fastenings 11, it being understood that such fastenings are provided both at the front and rear of the garment, as stated. The shoulder straps 12 75 extend from one bib to the other and as the front and rear portions are duplicated in all respects, it follows that if the garment is of sufficiently large size, it may be worn without regard to the front and back; without 80 interfering with the freedom of motion of the wearer; furthermore the garment can be made without increase of material as compared with overalls now in common use so that the cost of production will not be increased whereas the efficiency and durability 85 of the device may be materially enhanced.

I claim—

A reversible garment having leg portions and two bibs uniform in construction, shoulder straps connecting the bibs, said leg portions having an open crotch, fastenings at each side of the garment at the top and at the front and rear of the crotch. 90

In testimony whereof, I affix my signature 95 in the presence of two witnesses.

PETER L. DE VOIST
